UNITED STATES PATENT OFFICE.

CHARLES EISLER, OF NEWARK, NEW JERSEY.

HEAD FOR CONSTRUCTING INCANDESCENT ELECTRIC-LAMP STEMS.

Application filed March 29, 1924. Serial No. 702,763.

To all whom it may concern:

Be it known that I, CHARLES EISLER, a citizen of the United States, and a resident of Newark, county of Essex, and State of

5 New Jersey, have invented a new and useful Improvement in Heads for Constructing Incandescent Electric-Lamp Stems, of which the following is a specification.

10 My invention relates to apparatus for the construction of incandescent electric lamp stems, and particularly to a head for assembling and uniting the parts of stems to be used in tipless incandescent electric lamps, that is to say, lamps having no sealing tip or 15 teat in the head of the bulb.

The stems for such lamps are made up of 20 four parts, which, in the operation of the device of the present invention, are held and welded together, the product of such 25 assembling and welding operation being collectively designated as a stem. The stem parts comprise a piece of glass tubing flanged outwardly at one end and designated as a flare, a sealing off tube inserted into the flare from the flanged end, a pair of electric current lead wires, and a glass rod or cane inserted in the flare from the opposite end thereof and serving to support the lamp filament.

30 In making an incandescent lamp stem, the glass rod or cane is inserted a short distance into the flare through its straight or inner end, the small diameter glass sealing off tube is inserted into the flare through its 35 flanged end up to about the glass rod, and the lead wires are passed through the length of the flare, so that they project a substantial distance from both ends thereof. With the parts so held in assembled relation, heat 40 is applied to the straight end of the flare and the heated parts are united by being pressed together while hot. While the closed portion of the flare is still hot, compressed air is forced inwardly through the 45 sealing off tube, resulting in an aperture being blown in the wall of the flare and forming a continuation of the bore of the glass sealing off tube.

The completed stem is adapted for use 50 by incandescent lamp makers, who, after mounting the filament structure on the glass rod or cane and connecting up the lead wires, insert the stem into the mouth of the lamp bulb and seal it thereto by application of heat. The air in the bulb is then exhausted or replaced with a suitable gas

through the sealing off tube, which communicates with the interior of the bulb through the aperture in the flare. The sealing off tube is sealed off and the metallic 60 socket portion of the lamp is inserted in place thereon, completing the electric lamp. The present invention, however, relates only to the making of the "stem", and is not concerned with the subsequent steps of completing 65 the lamp.

My improved device for making the tipless lamp stems, is known as a "head". In the machine in which these heads are preferably used, a number of the heads are 70 mounted on a rotating plate, and the successive operations in the making of the stems are performed as the revolving plate brings each head into a particular position with respect to blow torches and other devices 75 mounted preferably on the machine base on which the revolving plate and the heads are mounted. Except at the loading and unloading station, the heads are also axially rotated with respect to the plate while they 80 are traversing the deferent of the rotating plate. Various other means may be resorted to for facilitating the successive operations, such as by moving each head independently 85 into the desired positions, or by moving the heating and other devices with respect to stationary heads, or by a combination of these movements. Such machine as a whole is not of the present invention, which relates particularly to the heads for use in machines 90 of this general character.

An object of the invention is to provide means for efficiently bringing together and holding in assembly relation and uniting the parts making up the entire stem, all in one 95 head, without resorting to a multiplicity of machines and operations.

Another object is to provide a simple, compact and inexpensive device with a few simple adjustments for making stems of 100 various sizes and shapes, which could heretofore be accomplished only by expensive hand labor and an expenditure of considerable time and effort.

One feature of the invention is a novel 105 means for holding the sealing off tube suspended in position in the flare during the operation of closing the flare end and embedding therein the tubing, rod and lead wires, which is known as the "welding" operation. This tube suspending device is so arranged that the operations of moving 110

same into positions for, respectively, suspending the tube within the flare, and for carrying same out of the way to permit removal of the completed stem, and of clamping and unclamping the tube may be carried out manually in a simple manner and preferably by simple movements of one hand of the operator. While the device is described herein as being operated manually, it is understood that mechanical or other movement may be employed for the same purpose, and with the same result.

Other features of the invention will be referred to in the following description.

In the accompanying drawings, I have illustrated an embodiment of my invention, but it is to be understood that the apparatus shown is intended only for the purpose of illustrating and affording an understanding of the invention, and is not intended for limitation of the scope of my invention, which is as defined in my claims.

In said drawings, Fig. 1 is a front elevation of a stem head. Fig. 2 is a side elevation of a stem head with the tube holding means broken away. Fig. 3 is a plan view of a stem head with the tube holding means in alignment with the other stem parts and a tube inserted therein. Fig. 4 is a plan view, with the tube holding means swung into an out of the way position. Fig. 5 is a cross-section on the line 5—5, Fig. 1. Fig. 6 is a cross-section on the line 6—6, Fig. 1. Fig. 7 is a front elevation of the pocket member for receiving the filament cane and lead wires. Fig. 8 is a cross-section of the pocket member on the line 8—8, Fig. 7, showing a completed stem in place therein. Fig. 9 is a detail view of a modified form of pocket member, and Fig. 10 is a cross-section of the tube holding means on the line 10—10, Fig. 3.

In general the operation of the device of my present invention is as follows:

A glass rod is placed into the central bore of the pocket member, with its upper end projecting somewhat therefrom, and a flare is inserted with its flanged end uppermost into a pair of clamping jaws and with its straight end resting on the pocket member, so that the rod extends for a short distance upwardly into the flare. Two lead wires are inserted through the flare into smaller bores provided therefor in the pocket member, one on each side of the central bore. A slender glass tube is placed in a jaw holder provided for this purpose and same is held in suspended position from above the flare, with its lower end extending thereinto. Heat is applied to the lower end of the flare by a blow torch and when the parts are sufficiently hot, a pair of press jaws compress the lower end of the flare, closing it up and embedding therein the glass tube, rod and lead wires. Compressed air is then

forced inwardly into the glass tube, resulting in an aperture being blown in the flare wall in the vicinity of its closed end. The stem is allowed to cool slowly so as to avoid cracking, and is removed from the stem head.

For a better understanding of my invention, reference may now be had to the drawings, which show in detail an embodiment of my invention.

The stem head frame 10 is of generally T-shape. Same is preferably a metal casting and comprises a shaft portion 12, adapted to turn in a suitable bearing in a rotating plate or the like (not shown), and is provided with a pinion 14 and a bearing collar 16. From the bearing collar 16 a pair of separated standards 18, 18 extend upwardly and are joined by the cross-head 20. The cross-head portion 20 is provided with a bore 22, and a bore 24 in alignment with bore 22 is provided in the collar and shaft portion 16, 12 of frame member 10.

Means are provided for holding the glass cane 26 and lead wires 28, 28 in place, comprising a pocket member 30, adapted to be received in the bore or recess 22 in the cross head 20 of frame 10, and same may be fastened therein by set screw 32. (Fig. 4). Pocket member 30 is tapered off at each side of its upper end, as shown at 34, 34, and has a central bore 36 therein to receive the cane 26. Smaller bores 38, 38, one on each side of bore 36, are provided in pocket member 30 to receive the lead wires 28, 28. The bore 36 of pocket member 30 is enlarged at its lower portion, as indicated at 40. Said enlarged bore part 40 receives the guide pipe 42, fastened in pocket member 30 by set screw 44, and having a central bore 46 forming a continuation of pocket member bore 36.

The guide pipe 42 is provided with slideable gauge and stop devices for the glass cane 26 and lead wires 28. Lead wires 28 preferably extend somewhat beyond the end of the cane 26 to provide sufficient length for making the filament connections. In the form shown, guide pipe 42 is provided with a diametrically extending longitudinal slot 48. The stop or guide member 50 serving as a stop or gauge for the lead wires 28 is preferably of substantially cup form provided with a recess 52 and a bottom opening 54 of form adapted to receive and slide on the guide pipe 42. A pin 56, preferably a cotter pin, extends through openings 58 in the upper portion of cup 50 and through the slot 48 in guide pipe 42. Such pin 56 serves two functions: it acts as a stop or gauge for the cane 26, and also serves to position the bottom wall 60 of recess 52 a suitable distance beyond the end of cane 26, so that the lead wires 28, extending to the bottom wall 60 of cup recess 52, may project for a suit-

able length beyond the end of cane 26 and be suitably secured to the filament wires. Means, as the set screw 62, are provided for adjustably holding these parts in adjusted 5 position. Any desired length of glass cane 26 with the suitable somewhat longer length of lead wires can be secured by moving the parts just described up or down on the guide pipe 42 and securing them in place by the 10 set screw 62.

When it is desired, as with certain forms of lamps, to make stems having no glass cane or a short one, and short lead wires, a pocket member 30', such as shown in Fig. 9, 15 is used. Pocket member 30' has a central bore 36' through its entire length, and two smaller bores 38', 38', one on each side of bore 36', going only partially through the 20 length of pocket member 30'. The depth of bores 38', 38' gauges the length of the lead wires which are received therein, and the length of the glass cane received in bore 36' is gauged by a gauge pin 56' slidably 25 mounted in bore 36' and fastened therein in any desired position by a set screw. A transverse slot 48' is provided in pocket member 30' to assist in setting pin 56' for gauging the length of the glass cane entering bore 36'.

30 The means for holding the flare in place comprise a pair of clamping levers 64, 66, pivoted at 68, 68 in the standards 18, 18, and working in slots 70, 70 in the horizontal arms 72, 72 of the crosshead member 20. The 35 clamping jaws 74, 74 of clamping levers 64, 66 have V-shaped notches 76 in their gripping faces, in which the flare 78 is held. Clamping jaws 74, 74 are removably fastened to clamping levers 64, 66 by screws 80, 40 so that flares of varying diameters and contours can be clamped therein by simply replacing jaws 74 with jaws of the appropriate size or shape. The pivoting portion 82 of clamping lever 66 has a tooth 84, which 45 registers with a notch 86 in pivoting portion 88 of clamping lever 64, so that both clamping levers 64, 66 are operated upon manually pressing together knobs 90, 90. Spring 92, hooked into perforated lugs 94, 94 on 50 clamping levers 64, 66, serves to exert a spring tension on the clamping levers 64, 66 to hold a flare inserted therein, and also to return clamping levers 64, 66 to their closed 55 position when the flare is removed therefrom. The dotted lines in Fig. 1 indicate the fully opened position of clamping levers 64, 66 ready for insertion of the flare 78 therein.

60 The means for closing the straight end of the flare after same is heated and embedding therein the rod, tube and lead wires, comprise a pair of pressing jaws 96, 96, pivoted at 98, 98 on extensions 100, 100 on the crosshead portion 20. Press jaws 96, 96 are actuated by links 102, 102 pivotally connected at

one end to jaws 96, 96 and at the other end to cross bar 104. Bar 104 is mounted on slide bar 106, which slides in recess 24 in the shaft portion 12 of frame 10. To close press jaws 96, 96, as shown in solid lines in Fig. 2, 70 slide bar 106 is pushed upwardly, as by a cam or other means, and when the upward pressure on slide bar 106 is removed, the press jaws 96, 96 will open by gravity into the position shown in dotted lines in Fig. 2, 75 due to the fact that the link 102 is pivoted to the press jaw 96 at a point well outside the pivot point 98 and never comes to or passes a dead center. Thus the necessity of an additional spring or other device to return the press jaws 96, 96 to their open position, is obviated. In order to gauge the space to be left between press jaws 96, 96 when in closed position, which determines the thickness of the closed end of the flare 80 after the welding operation, screws 108 with lock nuts 110 are provided in one or both of the press jaws 96, 96.

85 The means for holding the glass tube 111 in place during the welding or closing of the flare is designated generally by numeral 112. Same comprises a slender shaft 114 adapted to turn in a sleeve 116 upon the manual application of comparatively light pressure thereto. Such sleeve 116 is itself mounted to turn in bearings 118 and 120 in extensions 122, 124 respectively of frame 10, but is so arranged as to require for its turning the application of a considerably increased manual pressure, as compared with 90 that sufficient for turning shaft 114.

95 One mode of securing this result is by providing sleeve 116 with notched out parts or recesses 126, 128, which are adapted to be engaged by a ball 130 spring pressed toward sleeve 116 by spring 132 located in a recess 134 in extension 124 of frame 10. In this way the holder 112 is releasably held in position over the pocket member 30 and in 100 swung away position respectively.

105 Tube holder 112 performs three separate and distinct functions during the course of making the stem; first, clamping and holding the glass tube 111 during the welding operation, as shown in Fig. 3; second, release of the glass tube and swinging laterally out of its place over the pocket member 30 at the completion of the welding operation, as shown in Fig. 4, so that the stem 115 may be lifted out of the pocket member; and third, return of the holder 112 with its 120 jaw closed, into position directly over the clamping jaws and in readiness to be opened to take and hold the tube for making the 125 next lamp stem.

The manual actuating device for the tube holder is so arranged and constructed that its several movements may be performed by the use of one hand or digit. Said tube holder 112 is manually actuated by a crank 130

handle 136 fastened to the lower portion of shaft 114 by set screw 138. A yoke member 140 is mounted on the upper end of sleeve 116 to oscillate therewith and has a stationary jaw 142 adjustably fastened in its cut away portion 144. Crank 146 is fastened by set screw 148 to the upper end of shaft 114, above yoke 140, and turns with shaft 114. A movable jaw 150 is pivoted in slot 152 formed between the arms 154, 154 of yoke 140, and is connected to crank 146 by link 156, so that partial rotation of shaft 114 causes opening and closing of movable jaw 150 against fixed jaw 142.

15 A stop for the return movement of pivoted jaw 150 is provided, as by same coming into contact with the base of the slot 152 in yoke 140. The pivoted jaw 150 is normally held toward or against fixed jaw 142 by 20 means of a spring 158 encircling the lower portion of shaft 114, and held by one end in recess 160 of crank handle 136 and by the other end being received in a recess 162 in extension 164 on frame 10.

25 To perform the first movement of holder 112, namely, the insertion therein of a glass tube 111, handle 136 is moved inwardly slightly against the tension of spring 158, causing a partial turning of shaft 114 in its sleeve 116, and causing pivoted jaw 150 to move away from fixed jaw 142 and the glass tube 111 is manually inserted between the jaws 142 and 150. Upon release of handle 136, the jaws with the glass tube 111 in place 30 therein are held closed by spring 158. In this first movement, sleeve 116 and yoke 140 fastened thereto remain stationary, the only parts set in motion being shaft 114, crank 146 fastened thereto, link 156 and movable 35 jaw 150.

40 Upon completion of the welding operation, it is necessary not only to open jaws 142 and 150 to release glass tube 111, which is now a part of the completed stem, but 45 also to swing holder 112 laterally away from the clamping jaws 74 so that the completed stem may be lifted out of the stem head. The first of these functions is accomplished by an application of light manual pressure 50 to crank handle 136, which imparts rotation to shaft 114 to open jaws 142 and 150 to release rod 111. This brings movable jaw 150 into contact with the base of slot 152 in yoke 140, and when increased manual 55 pressure is applied to handle 136 to rotate shaft 114, movable jaw 150 bears hard against the base of slot 152 causing yoke 140 to turn with it, thereby overcoming the holding effect of spring tensioned ball 60 130, which was in recess 126, and rotating sleeve 116 in its bearings 118, 120, whereby holder 112 is swung into the position shown in Fig. 4 in which it is away from over the flare clamping jaws 74, 74. Holder 112 is 65 releasably held in this swung away posi-

tion by ball 130 engaging the second recess 128 in sleeve 116.

To return holder 112 into lateral alignment with the clamping jaws 74 in readiness for the making of the next stem, handle 70 136 is moved outwardly or away from the stem head by application of pressure thereto. The rotation of shaft 114 in the direction opposite to that when opening jaws 142 and 150, causes movable jaw 150 to bear 75 hard against fixed jaw 142, thereby moving yoke 140 and sleeve 116 with it, against the pressure of spring tensioned ball 130, which is moved out of recess 128 and engages recess 126 when the holder 112 is in the fully 80 returned position. A positioning stop 166 is adjustably fastened to sleeve 116 by set screw 168, so that when holder 112 is in position to hold the tube 111 in alignment 85 with the clamping jaws 74, as during the welding operation, its flat face 166' abuts against the flat surface 170 of extension 172 on frame 10, as clearly shown in Fig. 5.

The operation of a machine comprising 90 a plurality of stem heads is very simple. The stem heads containing the stem parts are preferably axially rotated, as by the pinion 14 on the shaft portion 12, during 95 the making of the stems, except when they reach the emptying and reloading station. This is so as to insure uniform heating of the flare and stem parts preliminary to and during the welding operation, as well as 100 during the annealing of the stem after the welding operation and before removal thereof from the stem head. This reduces to a minimum the possibility of cracking of the stems and results in the production 105 of a high-grade product with but small loss.

When the stem head reaches the discharge 110 and loading station, it ceases its axial rotation and the operator removes the completed stem and reloads the head by manual insertion of a glass rod and two lead wires in the pocket member, a flare between the clamping jaws, and a glass tube in the tube holder. The loaded stem head now begins 115 its axial rotation and is moved away from the operator and into position before one or more blow torches, where the stem parts are given a preliminary heating. The stem head is next moved into position before a stronger flame and when the flare end to be closed and the stem parts are sufficiently hot, the press jaws are momentarily forced together by a cam or other means, closing the flare end and embedding therein the 120 rod, tube and lead wires. Compressed air is forced inwardly through the tube until an aperture is blown in the flare wall and communicating with the bore of the glass tube. For annealing the stem, it is brought 125 before one or more blow torch stations hav- 130

ing flames of decreasing intensity, so as to avoid uneven or too rapid cooling of the stem. When the stem head with the completed and partially cooled stem therein reaches the discharge and loading station, the operator manually removes the completed stem and reloads the stem head with parts for making the next stem, and this cycle is repeated indefinitely.

10 I claim:

1. A turnable holder for the sealing tubes of incandescent lamp stems having means for releasably locking it in two positions, a spring closed clamp carried by said holder, means for turning the holder into one or another of such positions, and means for opening the clamp against its spring by initial movement of the holder turning means.

20 2. In a holder for a lamp stem part comprising a pair of jaws, means including a shaft for operating said jaws upon manual application of light pressure to permit insertion of a stem part therebetween, and means including a sleeve in which said shaft is mounted to turn to a limited extent for bodily moving the holder out of alignment with the other stem parts upon manual application of greater turning movement to said shaft.

30 3. In a holder for a lamp stem part comprising a pair of jaws, means including a shaft for operating said jaws upon manual application of light pressure to permit insertion of a stem part therebetween, and means including a sleeve in which said shaft is mounted to turn to a limited extent for bodily moving the holder out of alignment with the other stem parts upon a continued manual application to said shaft of greater turning movement.

40 4. In a holder for a lamp stem part comprising a pair of jaws, means including a shaft for operating said jaws upon manual application of light pressure to permit insertion of a stem part therebetween, means including a sleeve in which said shaft is mounted to turn to a limited extent for bodily moving the holder out of alignment with the other stem parts, and means for releasably retarding the movement of said sleeve during the application of light pressure.

50 5. In a holder for a lamp stem part comprising a pair of jaws, means including a shaft for operating said jaws upon manual application of light pressure to permit insertion of a stem part therebetween, means including a sleeve in which said shaft is mounted to turn to a limited extent for bodily moving the holder out of alignment with the other stem parts, and means including a spring tensioned ball for releasably retarding the movement of said sleeve during the application of light pressure.

6. In a head for assembly and welding together of incandescent electric lamp stem parts, a spring closed clamp for holding a stem flare, a pocket member for holding a filament cane and a pair of lead wires to extend within the flare, and a tube holder swingable into positions over and laterally away from the flare clamp respectively, said holder comprising a clamp supporting member and a spring closed clamp on said member, and common means for initially opening the last named clamp against its spring and serving also upon continued movement for swinging the head from over the flare clamp.

7. In a head for assembly and welding together of incandescent lamp stem parts, a flare clamp for receiving and holding a flare, a pocket member for receiving and holding a filament cane and lead wires, and a tube holder movable into and out of alignment with said flare clamp and pocket member.

8. In a stem head for incandescent lamp stem making, a rotatable clamp carrying member, a tube holding clamp carried thereby comprising a pivoted jaw, and means for initially turning said jaw on its pivot and thereafter rotating the clamp carrying member.

9. A holder for a lamp stem part comprising a pair of jaws, a sleeve and a shaft rotating therein, means operated from said shaft for opening said jaws by a light manual application of pressure, and holder turning means operated from said shaft whereby a continued application of greater pressure will cause the holder to move bodily out of alignment with the other stem parts.

10. In a holder for a lamp stem part comprising a pair of jaws, a sleeve and a shaft rotating therein, means on said shaft whereby upon application of light manual pressure the jaws are operated, and whereby upon continued application of increased pressure the holder is moved bodily out of alignment with the other stem parts, and spring actuated retarding means for said sleeve whereby the movement of said sleeve is retarded so that movement of said jaws takes place in advance of the sleeve movement.

11. In a holder for a lamp stem part comprising a fixed and a pivoted jaw, a sleeve and a shaft rotating therein, means on said shaft for actuating the pivoted jaw upon application of light manual pressure, and means on said sleeve whereby upon continued application of increased manual pressure to the pivoted jaw causes the holder to move bodily out of alignment with the other stem parts.

12. In a holder for a lamp stem part comprising a fixed and a pivoted jaw, a sleeve, a shaft rotating therein and a spring on said shaft, means on said shaft for actuating the

pivoted jaw against the tension of said spring upon application of light manual pressure, and means on said sleeve whereby continued application of greater manual pressure to said shaft, the pivoted jaw is actuated to cause the holder to move bodily out of alignment with the other stem parts.

13. In a holder for a lamp stem part comprising a fixed and a pivoted jaw, a sleeve, a shaft rotating therein and a spring on said shaft, means on said shaft for moving the pivoted jaw away from the fixed jaw against the tension of said spring to permit insertion therein of a lamp stem part upon application of light manual pressure, means on said sleeve whereby upon continued application of greater manual pressure to said shaft, the open pivoted jaw causes the holder to move bodily out of alignment with the other stem parts, and means comprising a ball and a spring to retard the movement of said sleeve and hold same in the positions into which it is moved.

14. A holder for a lamp stem part comprising a sleeve, a yoke and a fixed jaw on said sleeve, a shaft adapted to rotate in said sleeve, a spring on said shaft, and a movable jaw pivoting in said yoke and registering with the fixed jaw, a crank on said shaft, and a link connecting said crank with said movable jaw, whereby upon application of light manual pressure to turn said shaft the movable jaw is turned on its pivot against the tension of said spring and upon continuing and increasing the manual pressure the movable jaw is brought into engagement with said yoke member carrying the holder with it out of alignment with the other lamp stem parts.

15. A holder for a lamp stem part comprising a pair of jaws, a sleeve having recesses therein, a shaft rotating in said sleeve, a ball adapted to enter the recesses in the

sleeve, and a spring adapted to hold said ball toward the sleeve recesses, thereby retarding rotation of said sleeve and requiring application of substantially high manual pressure to dislodge said ball from the particular recess in which it is seated.

16. In a head for assembly and welding together of incandescent lamp stem parts, a flare clamp and pocket member for receiving and holding a flare, a filament cane and lead wires, a tube holder comprising a pair of spring closed clamping jaws movable to bring said clamping jaws into and out of alignment with said pocket member, and a common operating means for opening the jaws against the tension of the spring and for moving the holder to carry the jaws thereof laterally away from the pocket member.

17. In a head for assembly and welding of incandescent lamp stem parts, a spring closed clamp for holding a glass flare with its flared end up and its straight end down, means for holding a filament cane and filament lead wires to extend up within the bore of the flare from beneath, a holder for holding a sealing off tube over the flare with its lower end extending down therein, said holder comprising a rotatable sleeve spring held in two positions and having thereon a clamp supporting member carrying a two-part clamp, a cranked shaft extending through the sleeve and arranged upon being turned to first actuate the clamp in the clamp supporting member and thereafter in a continuation of like movement to effect the turning of the sleeve to bring the clamp supporting member and clamp thereon laterally out of position over the flare holding clamp.

In testimony whereof, I have signed my name hereto.

CHARLES EISLER.
